VACUUM CLEANER

Gustaf Einar Lofgren, Riverside, Conn., assignor
to Electrolux Corporation, Dover, Del., a corpora-
tion of Delaware

Application November 10, 1934, Serial No. 752,437

6 Claims. (Cl. 15—158)

My invention relates to a cleaning tool or implement for use in connection with a vacuum cleaner. More especially, it relates to a new and improved form of brush nozzle.

5 Among the objects of my invention is the provision of a nozzle of this type in which the necessary parts are clamped together and in which no bolts or other special holding means are required, the resiliency of the various parts being relied upon for securing them together. Such type of construction not only gives a very neat appearance, but it also reduces materially the cost of 10 assembling the brush nozzle.

15 Further objects and advantages of my invention will be apparent from the accompanying drawing which forms a part of this specification and on which:

Fig. 1 is a cross-sectional view of a preferred embodiment of my invention; and

20 Fig. 2 is a perspective view of a part included in the device shown in Fig. 1.

Referring to the drawing, reference character 10 designates a member preferably made of sheet metal and stamped to the form of a hollow shell having a lower opening or mouth as shown and having an inner wall or inclined tubular portion 11 which is adapted to receive the end 12 of a suction hose or a usual rigid tubular handle member. The passage 26 formed by tubular portion 11 has a lower opening in a plane which is horizontal when the tool is in its normal position on a horizontal surface. Tubular member 11 is inclined so that handle member 12 may be held in a convenient inclined position. Member 10 25 also includes an outer wall or flange 13 which is generally concentric with inner wall 11 and which has a lower edge 14 in a plane parallel to the plane of the opening of tubular portion 11. The main part of flange 13 may be said to be inclined the same as tubular portion 11. The lower edge 14 of the flange is brought inwardly 30 toward the center of the tool so as to have a smaller diameter for reasons which will presently appear.

45 A member 15 is formed with a substantially spherical portion 16 which may be said to constitute the central part of the tool. Integral with spherical portion 16 is a more or less laterally extending flange portion or annular bridge member 17. At approximately the boundary between the spherical and flange portions, member 15 is formed with a circular groove or recess 18 for receiving the lower edge of tubular portion 11. Flange portions 17 is adapted to embrace the lower end of flange or wall 13, contacting the

wall on both the inside and outside thereof, as is clearly shown in the drawing. Flange portion 17 thus forms a groove or recess into which wall 13 extends.

The opening 19 in the lower end of the 5 hollow member is bounded by a reinforcing bead 20.

A circular holding member 21 in the form of a ring split at 21' and having a U-shaped cross-section supports a ring of brush bristles 22. 10 Member 21 is preferably made of metal and hence somewhat resiliient. The bristles are looped around a center wire 23 and the open ends of member 21 are brought together to securely clamp the looped portions of the bristles in place. 15 The holding member 21 is clamped within the lower opening or mouth of shell 10 adjacent to the flange or wall 13 with a part of the lateral flange portion 17 of hollow member 15 between member 21 and wall 13. The thickness of the 20 hollow member and the relative diameters of holding member 21 and flange 13 are so chosen that, once the holding member has been forced past the lower edge 14 of smaller diameter and into the position shown in the drawing, which 25 may be done by slightly compressing the ring to reduce its diameter by forcing the split ends 21' together, it will be securely clamped by the flange with the hollow member acting in the nature of a packing therebetween. If the hollow 30 member is made of rubber, the holding member 21 may be more readily forced into place by wetting the rubber with alcohol. This acts as a lubricant and permits the holding member 21 to be readily slipped into place. When in place, the resiliency of the holding member causes it to tend to expand to the diameter which it has in 35 unstressed condition, whereby the ring is securely held in place, the smaller diameter of the lower edge 14 aiding in preventing its removal. The 40 lateral flange 17 of hollow member 15 is preferably formed with a thickened portion or portions, preferably formed by ribs 24 on the outside of that part of the lateral flange which contacts the outside of flange 13. These thickened portions 45 increase the strength of the hollow member at this point and cause it to tightly grip the flange. This part of the hollow member also serves as means for protecting furniture which may be accidentally contacted by the tool. 50

The spherical part of hollow member 15 extends within the ring of bristles 22 and serves to support them when they are pressed against and moved over a surface being cleaned. This spherical part prevents the bristles from being bent at 55

sharp angles, which would be injurious to the bristles.

The lateral flange 17 of hollow member 15 serves to completely close the space between inner 5 wall 11 and outer wall 12 of member 10, thereby preventing the accumulation of dirt within this space. Consequently, it may be said that the web or flange 17 extends across the mouth of shell 10.

It will be noted that the various members making up the brush are held together entirely by frictional clamping and that no separate fastening means such as bolts or rivets are required. As has been previously pointed out, the absence of such fastening means not only improves the 15 appearance of the tool, but also reduces the cost of assembling the various parts.

While I have shown and described one preferred embodiment of my invention, it is to be understood that this has been done for the purpose of illustration only, and that my invention is to be limited only by the appended claims when viewed in the light of the prior art.

What I claim is:

1. A brush including a shell having spaced 25 walls defining an annular chamber between them and a central suction passage, a substantially annular bridge member bridging said annular chamber, a bristle holder within said chamber, with a portion of said bridge member between 30 the same and the outer wall whereby the parts are maintained in position with the bridge member in contact with the inner and outer walls.

2. A brush including a shell having spaced walls defining an annular chamber between them 35 and a central suction passage, a substantially annular bridge member bridging said annular chamber, a bristle holder within said chamber, with a portion of said bridge member between the same and the outer wall whereby the parts are

maintained in position with the bridge member in contact with the inner and outer walls, said bridge member being formed of resilient material and having its inner portion forming at least a part of the suction nozzle.

3. A brush as defined in claim 1 in which said outer portion of said bridge member overlaps the edge of said outer wall to provide a guard.

4. A brush nozzle including a shell having an inner wall defining a suction passage and an outer wall spaced from said inner wall, said walls being joined together at one end, a bristle holder within the space between said walls, a bridge member of flexible compressible material having an outer portion disposed between said bristle 15 holder and said outer wall for frictionally retaining said bristle holder, and having an inner portion engaging said inner wall, and a flexible hollow part connected to said inner portion, said hollow part forming a flexible continuation of 20 said suction passage.

5. A brush as defined in claim 4 in which the bridge member and hollow part are integral and made of rubber.

6. A brush nozzle including a shell of rigid 25 material having an inner wall defining a suction passage and an outer wall spaced from said inner wall, said walls being joined together at one end, the free ends terminating in substantially the same plane, a substantially annular rubber bridge 30 member overlying the free end of said outer wall and engaging and being supported by the free end of said inner wall, and a resiliently expandable bristle holder within the space between said walls, a portion of said rubber bridge member 35 being clamped between said resilient holder and said rigid outer wall, and providing frictional engagement with said holder and outer wall.

GUSTAF EINAR LOFGREN.
